UNITED STATES PATENT OFFICE

162,335

KITCHEN RANGE

Enos G. Neto, Taunton, Mass.

Application April 24, 1950, Serial No. 9,437

Term of patent 3½ years

(Cl. D81—4)

To all whom it may concern:

Be it known that I, Enos G. Neto, a citizen of the United States, residing at Taunton, in the county of Bristol and State of Massachusetts, have invented a new, original, and ornamental Design for a Kitchen Range, of which the following is a specification, reference being had to the accompanying drawing, forming part thereof.

Figure 1 is a front elevational view of a kitchen range, showing my new design.

Figure 2 is a side elevational view thereof, and Figure 3 is a top plan view of the same.

The appearance of the side of the kitchen range not shown is substantially the same as the side shown.

I claim:

The ornamental design for a kitchen range, as shown and described.

ENOS G. NETO.
